ATTORNEYS.

UNITED STATES PATENT OFFICE.

NILS T. TRYGGE, OF CHICAGO, ILLINOIS.

PENCIL ERASER.

Application filed May 4, 1920, Serial No. 378,935. Renewed July 26, 1923. Serial No. 557,733.

To all whom it may concern:

Be it known that I, NILS T. TRYGGE, a citizen of the United States, residing at Chicago, in the county of Cook and State of Illinois, have invented new and useful Improvements in Pencil Erasers, of which the following is a specification.

This invention relates to lead pencils which are provided with eraser tips, and its object 10 is to provide a device of this kind which is especially adapted for drawing pencils, and also to provide the device with an eraser rubber which can be cheaply applied.

The object stated is attained by means of 15 a novel combination and arrangement of parts to be hereinafter described and claimed, and in order that the same may be better understood, reference is had to the accompanying drawing forming a part of this 20 specification.

In the drawing,

Figure 1 is an elevation of a fragment of a lead pencil showing my improved eraser tip applied thereto;

Fig. 2 is a longitudinal section thereof, and 25 Fig. 3 is a cross section on the line 3—3 of Fig. 1.

Referring specifically to the drawing, 5 denotes a drawing pencil which is of hexagonal or other polygonal cross-section, as 30 usual. To the butt end of the pencil is fitted a ferrule 6 having a projecting portion 7 which carries the eraser rubber 8. The part 7 is corrugated to obtain a tight 35 grip on the rubber 8, and if desired these corrugations may be helical similar to a screw-thread.

In order to reduce the cost of the rubber 8 to a minimum, its portion 9 which is held

in the ferrule extension 7 may be a cheaper 40 quality of rubber, a good grade of rubber being employed only for the projecting portion which is in actual use; or any other suitable cheap material may be substituted for the inner portion 9 of the rubber. It will 45 be understood of course, that the two sections of the rubber will be united to form one integral plug.

The ferrule 6 is polygonal in cross-section to conform to the cross-sectional contour of 50 the pencil 5, and its inner end or edge is rounded off to prevent catching on anything when the pencil is taken out of a pocket or handed to some one. The ferrule also has an opening 10 to expose 55 the usual number imprinted on the pencil to denote its hardness. The ferrule will also have a slight taper so that it must be forced on the pencil, with the result that 60 it is tightly held in place thereon.

That portion of the ferrule 6 immediately 65 to the rear of the butt end of the pencil 5, has a deep circumferential indentation 11 forming a stop to limit the extent to which 70 the pencil may be inserted.

I claim:

An eraser tip for lead pencils comprising 75 a ferrule adapted to be fitted over the butt end of a pencil to project therefrom, and an eraser rubber held in the projecting portion 80 of the ferrule and projecting therefrom, that portion of the rubber which seats in the ferrule being of a material different from 85 and inferior to that of the projecting portion thereof.

In testimony whereof I affix my signature.

NILS T. TRYGGE.
